UNITED STATES PATENT OFFICE.

ARTHUR E. ANAKIN, OF LONG BEACH, CALIFORNIA, ASSIGNOR, BY MESNE ASSIGNMENTS, TO SAFEWAY LOCK COMPANY, A CORPORATION OF NEVADA.

LOCK.

Application filed January 15, 1925. Serial No. 2,530.

This invention relates to improvements in locks.

It is an object of the invention to provide a lock having a bolt similar in construction to the bolt of an ordinary night latch, which will have mechanically operated means for throwing the bolt or sliding it into its keeper and then rotating the bolt after having entered its keeper; and to provide means for preventing unauthorized throwing of the bolt.

Another object of the invention is to provide a lock having a bolt upon which there is rotatably mounted a hardened ferrule, which ferrule is disposed about a bolt in such a position that it will be across the opening between the door and the door frame when the bolt is thrown so that because of the rotation of the ferrule, it will be impossible to saw the bolt through as by a hack-saw or the like.

A further object of the invention is to provide a lock having a bolt adapted to be thrown to lock the door, or other device upon which the lock is adapted to be mounted, which cannot be opened from the inside.

With the foregoing and other objects in view which will be made manifest in the following detailed description and pointed out in the appended claims, reference is had to the accompanying drawings for an illustrative embodiment of the invention, wherein:

Figure 1 is a vertical section through the door to which the improved lock has been applied;

Fig. 2 is a vertical section taken substantially on the line 2—2 of Fig. 1, and showing the keeper in section as associated with the lock;

Fig. 3 is a perspective view showing the bolt of the lock as having entered the keeper;

Fig. 4 is a perspective view of the keeper, parts being broken away and shown in section;

Fig. 5 is a view taken substantially on the line 5—5 of Fig. 1, showing the sleeve in which the bolt is slidable; and

Fig. 6 is a vertical section through the keeper taken substantially on the line 6—6 of Fig. 2.

Referring to the accompanying drawings wherein similar reference characters design-

nate similar parts throughout, a plate 10 is mounted upon the back or the inside face of the door D, which has downwardly inclined edges which hold the body of the plate in spaced relation to the face of the door. Upon the forward face of the plate 10, there is mounted a strip 12 which is secured to the plate 10 as by rivets 13. The strip 12 is bent forwardly from the plate 10 and cooperates with the plate to form bearings for a shank 14 which is rotatable. A lock 15 is mounted within the body of the door and projects slightly from the front face thereof. This lock may be of any conventional construction and may be operated by a key which is capable of causing rotation of the shank 14 in the bearings provided by the strip 12 and the plate 10. The shank 14 has a squared portion 16 between the strip 12 and the plate 10, and pins 17 project from the sides of the squared portion.

Links 18 are pivotally mounted upon the pins 17 upon the sides of the squared portion 16 and form a crank pivoted to the shank 14. Upon the back face of the plate 10 there is secured a bracket 19 having fingers 20 which project through slots formed in the plate 10 and are clinched upon the inner or forward side thereof. The bracket 19 serves to secure a sleeve 21 against the back face of the plate 10.

Within the sleeve 21 there is slidable a bolt 22. A member 23 is pivoted between the lower ends of the links 18 and is provided with a ball-shaped head 24. The ball-shaped head 24 projects through an arcuate slot 25 formed in the plate 10, and is received within a socket 26 mounted within the body of the bolt 22. The member 23 with its ball-shaped head and the socket 26 provide a universal joint connection between the crank formed by the links 18 and the bolt 22. A slot 27 having an angular extension 28 is formed in the sleeve 21, in which is slidable the ball-shaped head 24 of the member 23. The forward end of the bolt 22 is of a reduced external diameter 29, and a ferrule 30 which is preferably formed of hardened steel is rotatable upon this reduced portion. Lugs 31 are formed upon the top and bottom of the bolt 22 and serve to maintain the ferrule 30 upon the bolt.

The keeper consists of an inner member

2
32 having angular passages 33 formed therein, which angular passages give the appearance of a bayonet joint adapted to receive the lugs 31. The inner member 32 is rigidly held within an outer member or cap 34, which cap may be secured to a plate 35 by means of a bracket 36, the bracket 36 having fingers 37 extending through slots in the plate 35 and being clinched upon the under side thereof. The plate 35 with the keeper mounted thereon may be secured as by screws, bolts, or the like, upon the door frame opposite the bolt 22. When the bolt is in unlocked position, the links 18 forming the crank upon the shank 14 are extending downwardly and toward the left of the shank 14 when looking at the lock in the position shown in Fig. 2. Upon rotation of the shank so as to swing the links 18 downwardly, the bolt 22 is urged toward the right. The downward movement of the member 23 carried by the links 18 tends to rotate the bolt 22 as well as slide it within the sleeve 21. The socket 26 slidable within the slot or groove 27 formed in the sleeve 21 prevents rotation of the bolt 22 until the bolt has entered the keeper. After the bolt has entered the keeper, the socket 26 disengages from the sides of the slot 27 having entered the angular extension 28 formed in the sleeve 21. When the socket 26 has entered the angular extension 28, the links 18 will have been swung approximately 90° within the arcuate slot 25. The socket 26 having disengaged from the slot 27 then permits the bolt to rotate, which it is urged to do by the upward movement of the links 18 and the member 23 carried thereby. In this manner, the bolt 22 is caused first to slide without rotation into the keeper, the lugs 31 entering the straight passages 33' of the angular passages 33. Toward the end of the sliding movement, the bolt 22 is urged to rotate, and as there is nothing to prevent this rotation toward the end of the throwing of the bolt, the bolt 22 will rotate and the lugs 31 will enter the passages 33'' of the angular passages 33. The ferrule 30 occupies the position upon the bolt when the bolt is thrown, between the sleeve 21 and the keeper.

From the construction of the lock, it will be readily apparent that it is impossible to open the lock from the inside. This prevents thieves from entering a building, as in a store, and secreting themselves within the building until the owners have departed and then making their exit through the door with the stolen property. Furthermore, if a thief attempts to saw the bolt, as by inserting a hack-saw between the door and the door jamb, the movement of the saw will merely rotate the hardened ferrule 30 and will prevent sawing of the bolt.

When it is desired to unlock the lock, the

shank 14 is rotated in an opposite direction, which swings the links 18 from the right toward the left opposite the arcuate slot 25. The first movement of the links 18 produces rotation of the bolt so that the lugs 31 are withdrawn from the passages 33'' into the passages 33' of the angular passages 33. Further movement of the links 18 causes sliding of the bolt from the keeper, it being understood that when the lugs 31 are within the passages 33', the socket 26 is opposite, or in line with, the slot 27 formed in the sleeve 21.

From the above it is seen that an improved lock is provided having a bolt upon which a ferrule is rotatably mounted and that there is a rotatable shank associated with the bolt, having means connecting the shank to the bolt whereby the bolt will be first caused to slide into the keeper and after having entered it, will be caused to rotate therein. In this manner rotation of the shank 14 produces two separate movements of the bolt, namely, a sliding movement without rotation upon entering the keeper and rotation of the bolt with comparatively no sliding movement after having entered the keeper.

It will be understood that various changes may be made in the detail of construction without departing from the spirit or scope of the invention as defined by the appended claims.

I claim:

1. A lock comprising a sliding bolt, a rotatable shank, a crank pivoted to said shank, means forming a universal connection between said crank and said bolt, and a keeper for said bolt.

2. A lock comprising a sliding bolt, a rotatable shank, a crank pivoted to said shank, means forming a universal connection between said crank and said bolt, a keeper for said bolt, and means for preventing unauthorized rotation of said shank.

3. A lock comprising a sleeve, a bolt slideable in said sleeve, a rotatable shank, a crank pivoted to said shank, a ball and socket joint forming a universal connection between said crank and said bolt, a lug formed upon said bolt, a slot formed in said sleeve in which said lug is adapted to slide so as to prevent rotation of said bolt during part of its sliding movement, and means for preventing unauthorized rotation of said shank.

4. A lock comprising a sleeve, a bolt slideable in said sleeve, a rotatable shank, a crank pivoted to said shank, a ball and socket joint forming a universal connection between said crank and said bolt, a lug formed upon said bolt, a slot formed in said sleeve in which said lug is adapted to slide so as to prevent rotation of said bolt during part of its sliding movement, a keeper adapted to receive said bolt, lugs formed upon said bolt, pas-

sages formed in said keeper adapted to receive said lugs, and means for preventing unauthorized rotation of said shank.

5. A lock comprising a sleeve, a bolt slideable in said sleeve, a rotatable shank, a crank pivoted to said shank, a ball and socket joint forming a universal connection between said crank and said bolt, a lug formed upon said bolt, a slot formed in said sleeve in which said lug is adapted to slide so as to prevent rotation of said bolt during part of its sliding movement, means for preventing unauthorized rotation of said shank, and a ferrule rotatable upon said bolt as and for the purpose described.

6. A lock comprising a sleeve having a slot therein, a bolt slideable in the sleeve, a rotatable shank, and means connecting the shank to the bolt through the slot so that the bolt may be actuated thereby, whereby upon rotation of the shank, the bolt will be caused to slide in the sleeve and to rotate therein.

7. A lock comprising a sleeve having a substantially right angular slot therein, a bolt slideable in the sleeve, a rotatable shank, and means operatively connecting the shank to the bolt through the slot, whereby upon rotation of the shank, the bolt may be caused to slide in the sleeve and rotate therein.

8. A lock comprising a sleeve having a slot therein, a bolt slideable in the sleeve, a rotatable shank, an arm carried by the shank, and means connecting the arm to the bolt

through the slot, whereby upon rotation of the shank, the bolt will be caused to slide in the sleeve and rotate therein.

9. A lock comprising a sleeve having a substantially right angle slot therein, a bolt slideable in the sleeve, a rotatable shank, an arm carried by the shank, and means connecting the arm to the bolt through the slot whereby upon rotation of the shank, the bolt will be caused to slide in the sleeve and rotate therein.

10. A lock comprising a sleeve having a substantially right angle slot therein, a bolt slideable in the sleeve, a rotatable shank, an arm carried by the shank, means connecting the arm to the bolt through the slot whereby upon rotation of the shank, the bolt will be caused to slide in the sleeve and rotate therein, and a ferrule rotatable upon the bolt as and for the purpose described.

11. A lock comprising a sleeve, a bolt slideable in the sleeve, actuating means for sliding the bolt in the sleeve, there being a slot in the sleeve, said actuating means being connected to the bolt through the slot, and being so constructed that the bolt will be caused to slide and rotate thereby, the sides of the slot acting as a guide during the movement of the bolt.

In testimony whereof I have signed my name to this specification.

ARTHUR E. ANAKIN.
